HUBERT C. ELLIS, OF EVANSTON, ILLINOIS.

REVERSIBLE DRIVING MECHANISM FOR TUMBLERS.

Application filed February 26, 1927. Serial No. 171,109.

The invention relates to driving mechanism for reversibly driving tumblers, such as the cylinders of washing machines, driers, or the like.

- 5 One object of the invention is to provide mechanism of this type with improved controlling mechanism whereby the cylinder may be manually controlled to stop at a predetermined point.
- 10 Another object of the invention is to provide an improved brake for this type of driving mechanism which is operable by the lever which controls the automatic reversing mechanism and the manual control which will release the brake when the cylinder is being operated under automatic or manual control, and this object is attained primarily by providing a brake which is adapted to release in two alternate positions into which it is shifted by the controlling lever. Another object of the invention is to provide improved controlling mechanism which is operable to stop the cylinder at any time and which will always start the machine from a predetermined 25 point and in the same direction. Other objects will appear from the description.

The invention consists in the several novel features hereinafter set forth and more particularly defined by claims at the conclusion 30 hereof.

In the drawing: Fig. 1 is a side elevation of a machine embodying the invention, parts being broken away for illustrative purposes. Fig. 2 is a rear elevation. Fig. 3 is a plan of the driving mechanism. Fig. 4 is a section on line 4—4 of Fig. 3. Fig. 5 is a section on line 5—5 of Fig. 4. Fig. 6 is a detail of the cam and the shifter therefor which is operable by the manual control lever. Fig. 7 is a 35 plan of the automatic reversing device, the enclosing casing being shown in sections. Fig. 8 is a detail section of the adjustable connection between the slideable collar on the reversing shaft and the manually shiftable controller arm. Fig. 8^a is a section on line 8^a—8^a of Fig. 4. Fig. 9 is a sectional view, illustrating the brake for the cylinder. Fig. 10 is a section on line 10—10 of Fig. 9.

The invention is exemplified in connection 40 with a washing machine comprising a casing A which contains a washing cylinder (not shown) which is alternately operated in series of revolutions in opposite directions, as well understood in the art. The cylinder is driven from a shaft b through any suitable gearing, such as a pinion b' fixed to the shaft, an idler

gear b² and a gear b³ fixed to the shaft a' of the cylinder.

The drive-shaft b is journaled in suitable bearings a³ and a⁴. Bearing a⁴ is secured to a 60 pair of channel beams a² which are secured to a bracket a⁵ at either end of the casing A and which carries bearings a³. A drive pulley c is fixedly secured to the shaft b between two loose pulleys c' and c². The pulleys are each 65 confined by collars b²⁰ against longitudinal movement on the shaft b. The pulley c' is adapted to be driven by a crossed belt c³ and pulley c² by an uncrossed belt c⁴, usually from an overhead pulley, so that the belts will be 70 constantly driven in opposite directions. The shifting mechanism for the belts comprises a slide d, in one end of which is secured, by screws d³, a transverse arch-bar d'. A yoke d⁵ is adjustably secured by a set screw d⁶ 75 to the bar d' and is adapted to shift the belt c³. A yoke d⁷ is also adjustably secured by a screw d⁸ to the bar d' and is adapted to shift the belt c⁴. Belt c⁴ drives the loose pulley c² in one direction, and yoke d⁵ is adapted to 80 shift said belt from the loose pulley onto the drive pulley c, to drive shaft b in one direction. Belt c³ drives the loose pulley c' in the opposite direction, and yoke d⁷ is adapted to 85 shift said belt onto the drive pulley c to drive shaft b in the opposite direction. This exemplifies a series of pulleys by which the drive-shaft b may be alternately driven in opposite directions under automatic belt-shifting mechanism.

This belt-shifting mechanism comprises a 90 vertical shaft e which is journaled in a bearing e' on a bracket e² which is secured to the gear-housing e³; an arm e⁵ fixedly secured to the upper end of shaft e; and a link e⁶ which is pivoted to the distal end of said arm, and at e⁷ to a lug e⁸ on the slide d, to which the belt shifting bar d' is secured. Gearing for oscillating the shaft e to reciprocate the slide d is 95 continuously operated from the loose pulley c².

The gearing for operating the shaft e from pulley c² comprises a worm f which is free to rotate on shaft b and extends through one side of the housing e³ and is provided with 100 driving lugs f²⁰ which interengage with an adapter f' which is secured to the hub of the pulley c². Worm f meshes with a worm gear f² which is rotatably mounted on a stud-shaft f³ held in the back of the housing e³ and 105 carries an eccentric pin f⁴ which rotates continuously in one direction. The belt c⁴ is of 110

such width that, when it is shifted onto the drive pulley c , a sufficient portion will remain lapped around the loose pulley c^2 so that the worm gear connected to the pulley c^2 will be 5 constantly driven in one direction at all times while the belts are in operation; that is while the drive pulley c is stationary and while it is being driven in either direction by the belts. A shaft f^5 is journalled in a bearing e^9 at the 10 bottom of the casing e^3 and in a bearing e^{10} which is bolted to the front of the casing. A shifter member f^6 is fixed to the shaft f^5 and is provided with a pair of arms f^7 and f^8 which are extended vertically so as to be 15 engaged by the stud f^4 . The contiguous faces of these arms are co-relatively disposed so that the stud will operate the arm f^8 out of its path of rotation during one-half revolution of the stud and to simultaneously shift 20 the arm f^7 into position to be engaged by the stud during its next half revolution, and vice versa. As a result, the stud will, at the end of one-half revolution of the worm f^2 , shift the member f^6 alternately in opposite directions to rock the shaft f^5 .

A releasable coupling is provided between the shafts f^5 and e to control the automatic shifting of the slide d so that during normal operation, the belt shifting mechanism will 30 be automatically operated to shift the belts at the end of predetermined cycles and so that the belt-shifting mechanism may be disconnected. This coupling comprises a clutch collar g^3 pinned to the upper end of shaft f^5 , and a coacting clutch collar g^4 which is slidably mounted on, and splined to, the shaft e . When the clutch collar g^4 is raised, the interfitting teeth on the collars are disengaged so 35 that the shaft e will stop while the shaft f^5 will continue to rotate. Shafts e and f^5 are 40 coaxial or aligned, and the lower end of the shaft e is extended into the collar g^3 to provide a journal for the lower end of the shaft e .

The interfitting teeth of collars g^3 and g^4 are formed so that the shafts e and f^5 may be 45 coupled together only at a predetermined point so as to maintain the timed relation between the belt shifting mechanism and the gearing for automatically shifting it, as exemplified by the notch g^{30} in collar g^3 and a single tooth g^{40} on the collar g^4 . This construction permits the belt shifting mechanism to be manually manipulated at will independently of the automatic shifting mechanism 50 when the clutch collars g^3 , g^4 are uncoupled and also provides for coupling them together at one point only so that the shafts e and f^5 will be correctly connected for effecting the movement of the slide d , regardless of the position in which the slide d may stop. The casing e^3 is adapted to contain a lubricant, and is provided with a removable top cover 55 g^{31} to provide access to the gearing therein when desired.

60 The means for manually shifting the clutch

collar g^4 to control the operation of the machine comprises an arm h which is provided with forked terminals h' to engage trunnions h^2 on a collar h^3 . To adjust the clutch collar g^4 relatively to the arm h , collar h^3 is screw-threaded to a sleeve h^4 in which the collar g^4 is rotatable, the sleeve h^4 being confined against endwise movement in the collar g^4 . By rotation of the sleeve h^4 , the position of the collar h^3 may be adjusted to effect the proper 70 coupling of the clutch members g^3 and g^4 relatively to the control lever and connecting parts. Arm h has its rear end fixed to a slide h^5 which is vertically movable in a guide h^6 formed in the housing e^3 . A roller h^7 is held 75 in the upper end of the slide h^5 and is adapted to operate a cam l which is integrally formed with the slide d .

This cam comprises downwardly divergent or relatively angled surfaces l' and l^2 so that the roller h^7 may pass between these cam portions when the slide d is in any of its positions and will shift the slide into the neutral position as the roller h^7 enters the apex l^3 between the divergent surfaces l' and l^2 . The cam l is also provided with an inclined slot h^{10} which leads upwardly from the apex l^3 and is adapted to shift the slide d in that direction which will bring the belt c^4 onto and off the driving pulley c . The roller h^7 is adapted to be shifted into the apex l^3 to shift the slide d into neutral position and to be given an additional stroke, so that it will act in slot h^{10} and shift the slide d into and out of position to render the driving pulley c operative by the belt c^4 . This slot is 95 designed so that when the cylinder is to be operated under manual control, the drive pulley c will be operated in one direction only.

A control lever k is suitably fulcrumed, as at k' , to one side of the casing A and is provided with a finger controlled lock k^2 by which the lever k may, in conjunction with notches k^3 , k^4 and k^5 , be locked in three predetermined positions. This lever is connected to rock a rod k^6 which is suitably journalled in bearings k^7 by means of a link k^8 which is pivoted at k^9 to said lever, and arm k^{10} fixed to shaft k^6 and to which the link is pivoted, as at k^{11} . Shaft k^6 is connected to 110 operate the slide bar h^5 by means of an arm k^{12} fixed to rock-shaft k^6 and an adjustable link k^{13} between said arm and the lower end of said slide bar. When lever k is locked in notch k^4 , the slide bar h^5 will be raised sufficiently to uncouple the collar g^4 from the 115 constantly driven collar g^3 , and roller h^7 on said bar will be positioned in the apex l^3 of the cam l , at which time the slide d will be in its neutral position, so that both of the oppositely running driving belts will be 120 on the loose pulleys respectively. When the lever k is locked in notch k^5 , slide bar h^5 will be positioned to hold arm h in position to 125 couple the clutch collars g^3 , g^4 , so that the 130

slide d will be constantly reciprocated through shaft e , arm e^5 , and link e^6 , to intermittently shift the belt yokes to alternately shift the belts onto the drive pulley c so they will be alternately operated in reverse directions for predetermined cycles. In practice, it is necessary to stop the cylinder when it is to be loaded or unloaded, and the stopping of the cylinder may occur at any point, depending upon the time when the lever k is shifted into neutral position. The casings of machines of this character are usually provided with a door to provide access to the cylinder, and the latter is provided with a door which must be brought into registry with the door of the casing when the cylinder is to be loaded or unloaded. Therefore, it is desirable to control the operation of the cylinder manually to operate it into its correct position for loading and unloading. For this purpose, the controller lever k is operable forwardly towards the notch k^3 to shift the slide bar h^5 upwardly a sufficient distance to cause the roller to operate in the cam slot h^{10} to shift the slide d , so that the belt c^4 will pass onto the drive pulley c and operate the gearing for driving the cylinder in one direction. By manipulating the lever k , the operator can manually control the rotation of the cylinder into the desired position, this being generally known as "spotting" the cylinder. If desired, the lever k may be locked in notch k^3 , to operate the cylinder continuously in one direction. This exemplifies mechanism for manually controlling the belt controller slide which is automatically operable and by manual means which limits the rotation of the cylinder under manual control to one direction, so that the operator will always know the direction in which the cylinder will be rotated under manual control.

In controlling devices for a reversible gearing for cylinders, it is usually necessary to apply a brake to the cylinder at the time the cylinder is reversed or when it is stopped and to control the brake conjointly with the control for the driving mechanism. It is also desirable to provide that the brake shall be operable by the controller lever, and to provide for the release of the brake when the lever is set for automatic or manual control of the gearing. This feature is exemplified in the braking device which comprises brake drum m which is fixedly secured to the shaft b . One side of the drum is closed by a plate m' , which is secured by bolts m^2 to the bracket a^5 . Each brake shoe m^3 is pivoted to a stud m^4 which is fixed in the bracket a^5 . Each shoe is provided with a lining m^5 to engage the inner periphery of the brake-drum m . A spring m^6 is connected to the brake shoes to normally draw them together into releasing position. A sleeve m^7 is adjustably connected to the shoe by a screw-thread. Each sleeve

has slidable therein a stem m^8 which is provided with a head m^9 . A cross-pin m^{10} in each stem is confined in a slot m^{11} in the sleeve m^7 to limit the movement of the stem out of the sleeve. A spring m^{12} is interposed between each head m^9 and a sleeve m^7 . The heads m^9 are arranged opposite each other and are adapted to be spread apart to apply the brakes by a rocker or cam m^{13} . The application of the brake is effected through the springs m^{12} to insure a uniform gripping of the shoes against the drum. Cam m^{13} is fixed to a shaft m^{14} which is journaled in the bracket a^5 and operatively connected to the shaft k^6 so that the brake will be controlled by the lever k conjointly with the control of the reversible gearing. The connection between shafts k^6 and m^{14} comprises an arm m^{15} fixed to shaft k^6 , a link m^{16} pivoted to said arm, and an arm m^{17} fixed to shaft m^{14} of cam m^{13} . The rocker or double cam m^{13} is adapted to spread the heads m^9 to apply the brakes when the lever k is locked in neutral notch k^4 and to release the brakes when the lever is shifted forwardly from its neutral position to render automatic control operative and to also release the brakes when the lever is shifted rearwardly to manually control the gearing. This construction exemplifies a braking device which is controlled by the lever which controls the gearing and which is adapted to apply the brakes when the lever is in its neutral position and the cylinder is stopped, and to release the brakes when the lever is shifted in either direction from its neutral position, so that when the driving mechanism is being operated under automatic control or under manual control, the brake will be released and set whenever the control lever is shifted to its neutral position.

The operation will be as follows: When the lever k is in its neutral position and locked in notch k^4 , its connection with shaft k^6 will retain the slide h^5 in the position indicated by dotted lines in Fig. 5, so the clutch collars g^4 , g^5 will be disengaged so that shaft e will be idle and the belt shifter slide d will also be idle. In this position of the lever k , the roller h^7 will be disposed in the apex l^{13} of the cam l to hold the slide d in its neutral position, so that the oppositely running belts will be on the loose pulleys c' , c^2 respectively. In this position of the lever k , the shaft m^{14} will hold the double cam m^{13} in the position shown in Fig. 9, so that the brake shoes m^3 will be applied to the brake drum m to hold the shaft b against rotation in either direction. When it is desired to continuously operate the machine so that the cylinder will be operated in alternating cycles in different directions, the operator will shift the lever k into the position shown in full lines in Fig. 1. The shift of the lever k from its neutral position will operate the shaft k^6 which in turn

will operate the cam m^{13} to release the brakes and will lower the slide h^5 to bring the clutch collar g^4 into mesh with the clutch collar g^3 . The latter, rotating continuously, will, at the proper point, mesh with the collar g^4 . This clutching will cause shaft e to be intermittently oscillated with the shaft f^5 so that the slide d will be intermittently reciprocated to alternately shift the belt c^4 onto the drive pulley c for operation of the cylinder in one direction for the desired period and then simultaneously shift both of the belts to take belt c^3 off the drive pulley c and to shift the belt c^4 onto it. This operation will continue as long as the lever k remains in its neutral position. To stop the machine, the operator will shift the lever k to neutral position. This shift will set the brake and raise the arm h to uncouple the shaft e from the continuously operating shaft f , and the holler h^7 will engage either of the divergent surfaces l^1 , l^2 of the cam l , and pass into the apex l^{13} so that the slide d will be operated from any position into the neutral position and to render the drive pulley c inoperative by either of the oppositely running belts. It is usually necessary to spot the cylinder; that is to bring the door in the cylinder into registry with the door in the casing, to provide access to the entry of the cylinder, because the cylinder may stop at any point. For this purpose, the operator will grasp the lever k and push it backwardly from its neutral position. This shift of the lever will operate the double-armed cam m^{13} to release the brake and the slide h^5 upwardly to operate the roller h^7 so that it will act in the cam slot h^{10} to shift the belt shifter slide d in one direction so that a portion of the belt c^4 will pass onto the drive pulley c , so that the cylinder will be operated in one direction. When the correct point is reached, the operator will restore the lever k to its neutral position to stop the cylinder and operate the slide d to shift the belt c^4 off the drive pulley c .

The invention exemplifies reversible driving mechanism for cylinders. The operator, through a single lever, may manually control the belt shifters, the automatic belt shifting device and the brake for the driving mechanism; in which the manual control of the belt shifter is adapted to cause the cylinder to be rotated in one direction only, so that the operator will know in which the cylinder will revolve to its correct position for access; and in which the braking device is released when the control lever is shifted to set the automatic control, and when it is shifted to manually control the belt shifting mechanism.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In reversible driving mechanism, the combination of a shaft to be driven, mechanism for driving the shaft in opposite directions, reversing means, driven mechanism for automatically and intermittently operating the reversing means, to alternately drive the shaft in opposite directions, a control lever, means operable by the lever for manually operating the reversing means to operate the shaft in one direction only, and means operated by the lever for controlling the automatic operation of the reversing means.

2. In reversible driving mechanism, the combination of a shaft to be driven, mechanism for driving the shaft in opposite directions comprising a fixed pulley, loose pulleys, and oppositely running belts, reversing means, driven mechanism for automatically and intermittently operating the reversing means, to alternately drive the shaft in opposite directions, a control lever, means operable by the lever for manually operating the reversing means to operate the shaft in one direction only, and means operated by the lever for controlling the automatic operation of the reversing means.

3. In reversible driving mechanism, the combination of a shaft to be driven, mechanism for driving the shaft in opposite directions comprising a fixed pulley, loose pulleys, and oppositely running belts, belt shifting means to reverse the direction, and control the operation of the driven shaft, driven mechanism for automatically and intermittently operating the belt-shifting means, to alternately drive the shaft in opposite directions, a control lever, means operable by the lever for manually operating the reversing means to operate the shaft in one direction only, and means operated by the lever for controlling the automatic operation of the reversing means.

4. In reversible driving mechanism, the combination of a shaft to be driven, mechanism for driving the shaft in opposite directions comprising a fixed pulley, loose pulleys, and oppositely running belts, belt-shifting means to reverse the direction and control the operation of the shaft, driven mechanism for automatically and intermittently operating the belt shifting means, to alternately drive the shaft in opposite directions, a control lever, means operable by the lever for manually operating the reversing means comprising a cam by which the shifting means will be first operated into neutral position from any point, provided with means to shift the reversing mechanism to operate the shaft in one direction only, and means operated by the lever for controlling the automatic operation of the reversing means.

5. In reversible driving mechanism for tum-

- blers, the combination of a shaft to be driven, mechanism for driving the shaft in opposite directions, reversing means for the driving mechanism, driven mechanisms for automatically and intermittently operating the reversing means to alternately drive the shaft in opposite directions, a control lever, means operable by the lever for manually operating the reversing means, means operable by the lever for controlling the automatic operation of the reversing mechanism, a brake for stopping the shaft, and brake operating means operable by the lever to apply the brake when the lever and reversing means are in neutral position and to release the brake when the lever is shifted either to render the automatic mechanism operable or when the reversing means is manually operated by the lever. 6. In reversible driving mechanism for tumblers, the combination of a shaft to be driven, mechanism for driving the shaft in opposite directions comprising a fixed pulley, loose pulleys, and oppositely running belts, reversing means for the driving mechanism, driven mechanism for automatically and intermittently operating the reversing means to alternately drive the shaft in opposite directions, a control lever, means operable by the lever for manually operating the reversing means, means operable by the lever for controlling the automatic operation of the reversing mechanism, a brake for stopping the shaft, and brake operating means operable by the lever to apply the brake when the lever and reversing means are in neutral position and to release the brake when the lever is shifted either to render the automatic mechanism operable or when the reversing means is manually operated by the lever. 7. In reversible driving mechanism for tumblers, the combination of a shaft to be driven, mechanism for driving the shaft in opposite directions, reversing means for the driving mechanism, driven mechanism for automatically and intermittently operating the reversing means to alternately drive the shaft in opposite directions, a control lever, means operable by the lever for manually operating the reversing means, means operable by the lever for controlling the automatic operation of the reversing mechanism, a brake for stopping the shaft comprising a drum and a plurality of shoes, and brake operating means comprising a cam operated by the lever so as to apply the shoes when the lever and reversing means are in neutral position and to release the shoes when the lever is shifted either to render the automatic mechanism operable or when the reversing means is manually operated by the lever. 8. In reversible driving mechanism for tumblers, the combination of a shaft to be driven, mechanism for driving the shaft in opposite directions, reversing means for the driving mechanism, driven mechanism for automatically and intermittently operating the reversing means to alternately drive the shaft in opposite directions, a control lever, means operable by the lever for manually operating the reversing means comprising an element operable by the lever to apply the brake when the lever and reversing means are in neutral position and rotatable in opposite direction from its operative position so as to release the brake when the lever is shifted to render the automatic mechanism operable and when the reversing means is manually operated by the lever. 9. In reversible driving mechanism for tumblers, the combination of a shaft to be driven, mechanism for driving the shaft in opposite directions, reversing means, driven mechanism for automatically and intermittently operating said reversing means to alternately drive the shaft in opposite directions, a control lever, means operable by the lever for manually shifting the reversing means comprising a reciprocatory cam having divergent surfaces to shift the reversing means to its neutral position, and a cam-way extending in one direction from the apex of said divergent surfaces to shift the reversing mechanism to operate the shaft in one direction only, and means controlled by the lever for controlling the automatic operation of the reversing mechanism. 10. In reversible driving mechanism for tumblers, the combination of a shaft to be driven, mechanism for driving the shaft in opposite directions, comprising a fixed pulley, loose pulleys and oppositely running belts, belt shifting means to reversibly drive and control the shaft, driven mechanism for automatically and intermittently operating said means to alternately drive the shaft in opposite directions, a control lever, means operable by the lever for manually shifting the reversing means comprising a reciprocatory cam having divergent surfaces to shift the belt shifting means to its neutral position, and a cam-way extending in one direction from the apex of said divergent surfaces to shift the belt shifting means to operate the shaft in one direction only, and means operable by the lever for controlling the automatic operation of the belt-shifting means. 11. In reversible driving mechanism for tumblers, the combination of a shaft to be driven, mechanism for driving the shaft in opposite directions comprising a fixed pulley, loose pulleys, and oppositely running belts, belt-shifting means, driven mechanism for automatically and intermittently operating the belt-shifting means to alternately drive the shaft in opposite directions comprising a pair of aligned shafts, coupling members on the shafts respective-

ly, a control lever connected to shift one of the coupling members, and means operable by the lever for manually operating the shifting means.

- 5 12. In reversible driving mechanism for tumblers, the combination of a shaft to be driven, mechanism for driving the shaft in opposite directions comprising a fixed pulley, loose pulleys, and oppositely running belts, 10 belt shifting means, driven mechanism for automatically and intermittently operating the belt shifting means to alternately drive the shaft in opposite directions comprising a pair of aligned shafts, coupling members on 15 the shafts respectively, a control lever connected to shift one of the coupling members engageable at one point only, and means operable by the lever for manually operating the shifting means.
- 20 13. In reversible driving mechanism for tumblers, the combination of a shaft to be driven, mechanism for driving the shaft in opposite directions comprising a fixed pulley, loose pulleys, and oppositely running belts, 25 belt shifting means, driven mechanism for automatically and intermittently operating the belt-shifting means to alternately drive

the shaft in opposite directions comprising a pair of aligned shafts, coupling members on the shafts respectively, a slide to shift one of the members, a control lever connected to shift said slide, and means operable by the lever for manually operating the shifting means, comprising a cam operable by the slide.

30 14. In reversible driving mechanism for tumblers, the combination of a shaft to be driven, mechanism for driving the shaft in opposite directions comprising a fixed pulley, loose pulleys, and oppositely running belts, 35 belt shifting means, driven mechanism for automatically and intermittently operating the belt-shifting means to alternately drive the shaft in opposite directions comprising a reciprocating bar and a pair of aligned shafts, coupling members on the shafts respectively, a slide connected to shift one of the members, a control lever connected to shift said slide, and a cam operable by the slide for 40 manually operating the shifting means.

45 Signed at Chicago, Illinois, this 31st day of January, 1927.

50 HUBERT C. ELLIS.
